UNITED STATES PATENT OFFICE

106,826

DESIGN FOR A CARTON FOR TRANSPARENT DRINKING STRAWS

Otto W. Dieffenbach, Baltimore, Md.

Application June 10, 1935, Serial No. 57,211

Term of patent 14 years

To all whom it may concern:

Be it known that I, Otto W. Dieffenbach, a citizen of the United States of America, residing at Baltimore, in the State of Maryland, have invented a new, original, and ornamental Design for a Carton for Transparent Drinking Straws, of which the following is a specification, reference being had to the accompanying drawing, forming part thereof, in which:

Figure 1 is a top plan view of the carton for transparent drinking straws.

Figure 2 is a perspective view of the bottom of the carton from one corner thereof.

Figure 3 is a similar view of the top of the carton.

Figure 4 is a perspective view from one side of the carton.

Figure 5 is a transverse cross sectional view through the center of the carton.

The distinguishing features of the carton reside in the provision of openings in the top and in the bottom respectively, the bottom opening underlying the top opening, being separated from the inclined sides by marginal flat portions extending longitudinally of the box.

I claim:

The ornamental design for a carton for transparent drinking straws, substantially as shown and described.

OTTO W. DIEFFENBACH.
